UNITED STATES PATENT OFFICE.

ALFRED A. FAXON, OF PHILADELPHIA, PENNSYLVANIA.

DESIGN FOR A BOX.

SPECIFICATION forming part of Design No. 29,057, dated July 19, 1898.

Application filed June 3, 1898. Serial No. 682,497. Term of patent 3½ years.

To all whom it may concern:

Be it known that I, ALFRED A. FAXON, a citizen of the United States, residing in the city and county of Philadelphia, in the State of Pennsylvania, have invented and produced a Design for Boxes, of which the following is a specification.

The drawing is a view in perspective of a box embodying my new design.
10 The leading or material feature of the design of my box consists in an upwardly-extending rear panel A at its edges fashioned or shaped to the outline of the head and upper portion of the trunk of a human figure, and as to its front face provided with markings which depict the features of the head, and garments upon said trunk, and are arranged and proportioned to conform to the outline of the panel,—and in a front panel B 15 and as to the upper field b (extending from the upper edge of the panel downwardly for one-third of its height) is provided with markings that represent stars upon a plain back-ground,

and as to the lower field b' (extending from the lower edge of the upper field b to the foot of the panel) with markings that represent broad vertically-extending stripes, alternately dark and light in appearance.

The upper end of the front panel B is level 25 with the lower end of the upwardly-extending panel A, so that when viewed from the front the top c of the box is not visible while the ornamented front faces of the two panels merge into and constitute continuations of 30 each other.

Having described my invention, I claim and desire to secure by Letters Patent:

The design for a box, as herein shown and described.

In testimony that I claim the foregoing as my invention I have hereunto signed my name this 25th day of May, A. D. 1898.

ALFRED A. FAXON.

In presence of—

F. NORMAN DIXON,
THOS. K. LANCASTER.
